UNITED STATES PATENT OFFICE.

BENJAMIN GOLDBERG, OF NEW YORK, N. Y.

COMBINED MIDDY-BLOUSE, ROMPERS, AND SKIRT.

1,138,468.

Specification of Letters Patent.

Patented May 4, 1915.

Application filed December 1, 1914. Serial No. 874,984.

To all whom it may concern:

Be it known that I, BENJAMIN GOLDBERG, a citizen of the United States, and a resident of the city of New York, borough of 5 Manhattan, in the county and State of New York, have invented a new and Improved Combined Middy-Blouse, Rompers, and Skirt, of which the following is a full, clear, and exact description.

10 This invention relates to combination outer garments for children and misses and it deals more especially with a middy blouse garment that embodies a detachable skirt or detachable rompers, whereby the garment 15 can be worn with all three pieces or as only a two-piece garment with the skirt or the rompers attached to the blouse.

The general objects of the invention are 20 to provide a combination garment of the character referred to so as to be of neat and attractive appearance and readily convertible for athletic use with the rompers attached to the blouse, or as a more dressy apparel with the skirt attached to the blouse 25 with or without the rompers.

The blouse has an internal band adjacent 30 its waist portion provided with suitable fastenings whereby the rompers may be attached to the blouse, and at the bottom of the blouse is another internal band having 35 fasteners for enabling the skirt to be attached thereto over the rompers. As these two lower parts of the garment are separately attached they can be used singly or together with the blouse at the desire of the wearer, whereby the garment can be converted for gymnastic use or for regular wear.

With such objects in view and others which 40 will appear as the description proceeds, the invention comprises various novel features of construction and arrangement of parts which will be set forth with particularity in the following description and claims appended hereto.

In the accompanying drawing, which 45 illustrates one embodiment of the invention, and wherein similar characters of reference indicate corresponding parts in all the views, 50 Figure 1 is a front perspective view of the garment worn as a combined middy blouse, skirt and rompers; Fig. 2 is a perspective

view showing the combined blouse and rompers effect; Fig. 3 is a perspective view showing the manner of attaching the skirt to the 55 blouse; Fig. 4 is a view showing the manner of connecting the rompers to the blouse; and Figs. 5 and 6 are enlarged sectional views respectively on the lines 5—5 and 6—6, Figs. 1 and 2.

Referring to the drawing, A designates a middy blouse, B the skirt and C the rompers.

The blouse is clearly shown in Figs. 4 and 5 as being provided with internal bands 1 and 2 arranged respectively at the waist and 60 at the bottom edge of the blouse, and these serve respectively to attach the rompers and skirt to the blouse. The skirt B is of any approved design and is provided around its top with a band 3. The rompers are also of 70 ordinary design and have a waistband 4 which is provided with sockets 5 for engaging studs 6 on the internal band 1, although any other suitable fastening means may be employed to detachably connect the garments together. The band 3 of the skirt is 75 provided with sockets 7, as shown in Fig. 3, to receive the studs 8 of the internal band 2 of the blouse. It will thus be seen that the two lower parts of the garment are 80 separately and detachably connected with the upper part and can be worn together or independently, according to the use to which the garment is to be put at any given time, and in whatever form the garment is worn 85 it presents a neat and attractive appearance. If desired, a belt 9 can be stitched to the blouse on the outside at the waist portion to increase the attractiveness of the garment.

Having thus described my invention, I 90 claim as new and desire to secure by Letters Patent:

1. A combination garment comprising a blouse, rompers detachably connected to the blouse adjacent the waist, and a skirt detachably connected with the blouse at a point below the waist and covering the rompers.

2. A three-piece garment comprising a blouse, internal bands therein respectively at the waist and bottom of the blouse, and 100 separate garment pieces detachably connected with the respective bands, whereby the blouse can be worn with either one or both of said pieces.

3. A blouse for a multiple-piece garment, internal bands extending around the inside of the blouse adjacent the waist and below the same, fastenings on the bands, and a belt fastened around the outside of the blouse at the waist thereof.

In testimony whereof I have signed my

name to this specification in the presence of two subscribing witnesses.

BENJAMIN GOLDBERG.
